UNITED STATES PATENT OFFICE.

HERMAN JAKOBSSON, OF PHILADELPHIA, PENNSYLVANIA.

LIMBER.

1,251,890.

Specification of Letters Patent.

Patented Jan. 1, 1918.

Application filed February 28, 1917. Serial No. 151,409.

To all whom it may concern:

Be it known that I, HERMAN JAKOBSSON, a citizen of the United States, residing at Philadelphia, county of Philadelphia, and State of Pennsylvania, have invented a new and useful Improvement in Limbers, of which the following is a full, clear, and exact description, reference being had to the accompanying drawings, which form a part 10 of this specification.

The object of my invention is to provide an ammunition limber, for use with field artillery, so constructed that when it is placed in position for use, complete protection from 15 rifle fire and shell fragments from in front will be afforded to those engaged in withdrawing ammunition; at the same time so constructed that the means provided for protection may be advantageously used 20 when the limber is not supplying a gun.

Referring to the drawings in which I have illustrated my invention:

Figure 1 is a top view of a limber with ammunition chest in place.

Fig. 2 is a side view of the subject of Fig. 1.

Fig. 3 is a rear view of the limber and chest in service position, with protective means in position.

Fig. 4 is a side view of the subject of Fig. 3.

The limber is provided with the wheels *a* mounted on the ends of the axle *b*. To the bearings *i*, mounted on the axle, is suitably 35 fastened the draft pole composed of the member *c*, provided at its outer end with the projection *v* bored to receive the pin *w* and the downwardly and outwardly extending trail eye *x* into which telescopes the member *d* which in turn is provided at its outer 40 end with the cross bar *e* for man draft and the ring *f* for attaching drag ropes.

The two members, composing the pole, are 45 adapted to be telescoped when the limber is idle, the member *d* being turnable in the member *c* to bring the cross bar into vertical position to serve as a support or prop to maintain the limber in upright position. When it is desired to draw or transport the 50 limber, the members are extended, the member *d* being provided with a shoulder, which limits its extension and maintains the cross bar in a horizontal position when the member is extended.

55 The ammunition chest *g*, provided with compartments *m*, is fastened to the frame *h*,

which in turn is fastened at its forward end to the member *c* of the pole, and is carried by the bearings *i*. The hook *j* is fastened to the rear of the frame for the attachment of 60 a gun carriage. To the sides of the chest, near its top, is fastened the foot bracket *k* which extends beyond the rear end and is provided with the cross member *l*. To the top of the chest at *n* is hinged the short 65 cover *o*, and at *p* is hinged the long cover *q*. The cover *q* is provided with the hand holds *r*, the fastening devices *s* and the slot *t*. The cover *o* is adapted to slightly overlap the cover *q* to cover the slot *t*, and is provided 70 with the fastening devices *u*. The ammunition chest is composed of light armor plate, the bottom and covers being somewhat heavier than the sides.

In practice, when it is desired to supply 75 ammunition to a gun, the limber is drawn up to a point adjoining the gun, and the members of the pole telescoped. The chest is then tipped up until the cross member *l* of the foot bracket *k* contacts with the 80 ground, as shown in Fig. 4. The fastening devices, holding the covers, are then loosened and the short cover swung down against the foot bracket *k* where it is maintained by its own weight, and the long cover 85 raised until the projection *v* extends through the slot *t*; the cover is then maintained in position by passing the pin *w* through the projection. The limber will now have assumed the position shown in Figs. 3 and 4, 90 and it can be readily seen that the ammunition is completely exposed, while at the same time any one withdrawing it would be protected by the body of the chest and the covers now forming shields extending above 95 and below it.

Having now fully described my invention, what I desire to claim and protect by Letters Patent is:

1. An ammunition carrier comprising a 100 limber, a chest mounted thereon and turnable relatively thereto, a cover hinged to the forward end of said chest, and means independent of said chest to maintain said cover in open position to form a shield when 105 the chest is turned toward a vertical position.

2. An ammunition carrier comprising a limber, a chest mounted thereon and turnable from a horizontal toward a vertical position, a long cover and a short cover hinged 110 at the front and rear of said chest respec-

- tively, said covers being adapted when open to extend beyond the ends of said chest and form shields.
3. An ammunition carrier comprising a limber, a chest mounted thereon and turnable from a horizontal toward a vertical position, covers hinged to the ends of said chest and adapted to be opened to extend beyond the ends thereof and form shields.
- 10 4. An ammunition carrier comprising a limber, a chest mounted thereon, a bracket extending rearwardly from said chest, two covers on said chest, one being in length approximately equal to the rearward extension of said bracket and hinged to the rear of the chest, and the other being of greater length and hinged to the front of the chest,
- 5 15 20 25 30
- said bracket serving as a foot for the limber when tilted and the two covers in open position forming a continuous shield with the bottom of said chest.
5. An ammunition carrier comprising a limber, a chest mounted thereon and turnable from a horizontal toward a vertical position, covers hinged to the ends of said chest and adapted to be opened to extend beyond the ends thereof and form shields, a pole, a latch on said pole, said latch retaining one of said covers in upright position when open.
- In testimony of which invention, I have hereunto set my hand, at Philadelphia, on this 12th day of February, 1917.

HERMAN JAKOBSSON.
